United States Patent Office

Des. 206,911
Patented Feb. 7, 1967

206,911

PAIR OF EYEGLASSES

Robert H. Ramp, Pittsford, N.Y., assignor to Bausch & Lomb Incorporated, Rochester, N.Y., a corporation of New York

Filed Apr. 29, 1966, Ser. No. 2,066

Term of patent 14 years

(Cl. D57—1)

FIG. 1

FIG. 2

FIG. 3

FIG. 1 is a front view of a pair of eyeglasses showing my new design;

FIG. 2 is a side view of said eyeglasses taken from the right side thereof as viewed in FIG. 1; and

FIG. 3 is a top view thereof.

The side not shown has substantially the same appearance as the side shown.

I claim:

The ornamental design for a pair of eyeglasses, substantially as shown and described.
